UNITED STATES PATENT OFFICE.

FRANK M. KNOWLTON, OF SPENCER, MASSACHUSETTS.

TWINE TAKE-UP.

SPECIFICATION forming part of Letters Patent No. 664,872, dated January 1, 1901.

Application filed March 28, 1900. Serial No. 10,533. (No model.)

To all whom it may concern:

Be it known that I, FRANK M. KNOWLTON, a citizen of the United States of America, and a resident of Spencer, in the State of Massachusetts, have invented a new and useful Improvement in Twine Take-Ups, of which the following is a specification.

This invention relates to devices for retracting or "taking up" the free end of twine as used on the counters of stores and shops for tying up bundles and packages, so as to save time and twine by preventing the free end from becoming lost or snarled or from adhering to the clothing of customers, and thus being carried off out of reach.

The improved device is a simple automatic "take-up" adapted to be made at moderate cost, of attractive appearance, and free from liability to get out of order.

The invention consists in certain novel combinations of parts hereinafter set forth and claimed.

A sheet of drawings accompanies this specification as part thereof.

Figure 1 of the drawings is a small-scale elevation of the improved take-up, illustrating its external appearance. Fig. 2 is an axial longitudinal section of the same shortened by breaks; and Figs. 3 and 4 are cross-sections on the lines 3 3 and 4 4, respectively, Fig. 2.

Like letters and numbers refer to like parts in all the figures.

The improved take-up is in the form of a pendant, as shown in Figs. 1 and 2, and comprises an attaching-head A, a cylindrical body-tube B, and a terminal knob C, all of which are preferably and conveniently of sheet metal and may be permanently united with each other by solder or may be separable, if preferred.

The head A is perforated for the passage of nails or screws 1 and 2, Fig. 2, by which the take-up is attached to the ceiling of a store or shop convenient to the position of a salesman or wrapping-clerk.

Within the body-tube B there is a suitably-recessed body part D, preferably of wood, and within the latter a vertically-sliding weight E, a cushioning-spring F beneath said weight, and a guide-tube G, the latter communicating with the space above said body part D within the body-tube B and with the interior

of the knob C, which is preferably and conveniently hollow. The recesses of the body part D comprise a central guideway 3, loosely fitted to the weight E, and a bore 4 at one side, tightly fitted to the guide-tube G. A plug 5, which may be of wood, glued fast or otherwise secured within the lower end of the guideway 3, supports the cushioning-spring 60 F, which is preferably a short spiral spring of suitable wire.

Through a side opening 6 in the body-tube B the twine passes direct to the eye 7 at the top of the weight F, thence to an eye 8, which may be formed by an eye-screw on a level with said side opening, and thence through the guide-tube G to an escape-opening 9 in the extremity of the knob C, from which it normally hangs within reach.

The twine T may be taken from a ball, cone, or spool of any kind held in a basket or other receptacle or upon a spindle or from a twine-holder of any description through the customary tension device belonging thereto. When the free end of the twine is pulled, the weight E is first elevated until its eye 7 is on a level with the opening 6 and eye 8. The twine then passes as freely through the entire system as though taken direct from the ball, and when it is severed the surplus twine is taken up by the return of the weight E to its position of rest upon the cushioning-spring F.

The attaching-head A, body-tube B, and knob C may be made of different ornamental shapes. The body part D may be molded of suitable plastic material. The weight E and its guideway may be of any non-circular shape in cross-section, and other like modifications will suggest themselves to those skilled in the art.

Having thus described said improvement, I claim as my invention and desire to patent under this specification—

1. A pendent-shaped twine take-up comprising an attaching-head, a body-tube depending from said head and having a side opening near its upper end to admit the twine, a recessed body part, within said tube, provided with a guide-eye on a level with said side opening, a weight guided by said body part and having a guide-eye at top, a guide-tube extending downward through said body part, and a knob at the lower end of said

body-tube provided with an escape-opening in communication with the lower end of said guide-tube.

2. The combination, in a pendent twine take-up, of a sheet-metal body-tube, a recessed body part within said tube having a guideway extending lengthwise therethrough, a weight sliding in said guideway, a plug-supported cushioning-spring within the lower

end of said guideway, and a knob at the lower end of said body-tube masking the spring-supporting plug, substantially as hereinbefore specified.

FRANK M. KNOWLTON.
